CHARLES E. BURNS,

Fordeau & Fordeau.

Attorney

UNITED STATES PATENT OFFICE.

CHARLEY E. BURNS, OF HAYNESVILLE, LOUISIANA.

PUMP.

Application filed January 11, 1926. Serial No. 80,404.

My invention relates to pumps and in particular to a combined pump and sand dislodging device.

It is my object to provide a pump which 5 combines means for elevating sand and loose material and for loosening material at the same time.

It is a further object to provide a mechanism which can be easily renewed, which 10 will not stick within the pump casing and which can be repaired or re-sharpened at will.

Referring to the drawings:

Figure 1 is a side elevation of the complete device;

Figure 2 is an enlarged section on the line 2—2 of Figure 1, showing the lower end of the device;

Figure 3 is a similar view showing the 20 upper end of the device.

Figure 4 is a cross-sectional view taken on the line 4—4 of Figure 2 and looking in the direction of the arrows.

Figure 5 is a cross-section taken on the 25 line 5—5 of Figure 2 and looking in the direction of the arrows.

Referring to the drawings in detail, 1 is the pump casing, having a guide head 2, in which reciprocates the pump piston or 30 plunger 3 having an attaching eye 4 at the upper end. This plunger has, on either side thereof, guide ribs 5 which work within guide walls 6 in the head 2. This pump rod or piston 3 is provided with an internal passageway 7 sealed by a ball 8 at its upper end, which fits within a cup 9 beneath a retaining pin 10.

Within this aperture 7 rotates a worm carried on a shaft 11. This worm consists 40 of a straight wire or shoulder along its upper portion, marked 12, which becomes a spiral wire or worm 13 in the lower portion, being wound around the wire 11. This spiral wire works within a slotted sleeve 14 which has an end 15 in which is a slot 16 to receive this spiral wire. The lower end 45 of this sleeve 14 is provided with shoulders 17 engaging with corresponding shoulders 18 on a screw sleeve 19.

This screw sleeve 19 carries outwardly extending shoulders 20 at the lower end thereof, but is provided with an internal aperture 21 and an aperture 22 within the sleeve 14, so that the worm wire may pass there- 55 through freely and extend downwardly into

engagement with the cutting plate which is hereinafter described.

The plunger 3 has threaded on its lower end an outwardly extending shoulder 23 having a plurality of cutaway portions 24 on 60 the periphery thereof.

Below this shoulder but above the shoulder of a ring 25 carried on the screw sleeve 20 is a loosely fitting reciprocating collar 26 spaced at 27 from the plunger having an enlarged space 28 at the top thereof to provide a thin, upper, outer wall 29. This loosely fitting collar acts as a piston within the cylinder casing, one for lifting the sand and other materials which are stirred up or 65 broken up by the rotating cutter.

This rotating cutter consists of a spiral head 30 having cutter faces 31 carried on a cutter head 32 which is suspended by a sleeve 33 on the rod 11, which is rotated by the 70 spiral wire 13.

This rod is loosely guided by the guide plate 34 held within the cylinder.

The head 32 is guided by a similar transverse plate carried within a cylinder, as 75 at 35.

Side openings 36 are provided, through which access may be had to the detachable portion of the collar 26, which consists of the plate 29 forming the upper part of this 80 piston. It is held in position by screws 37.

The material which is dug up and lifted may be ejected through the exit openings 36.

In practice, as the plunger ascends and descends with its piston, the cutter knives 90 are rotated, cutting the material and also elevating it by reason of the screw. At the same time, the pump lifts this material and ejects it through the openings 36.

In case a well has enough fluid in it to 95 cover the pump before it reaches the bottom of the well, the fluid will enter through the opening 36 and the openings in the spider 35, in which instance very little if any sand will enter the pump. But when the depth 100 of fluid in the well is not sufficient to reach the opening 36 even when the pump is resting on the bottom of the well the fluid rises in the pump to its outside level through the openings in the spider 35 and carries with it 105 the sand which is being agitated and lifted by the member 30 and then drawn into the cylinder by suction. When the plunger is lowered should the cylinder be partly filled, the amount of sand slushing up in the open- 110

ing 21 would be so small it would not interfere with the operation of the pump.

At the top of the sleeve 14 is a bearing against which the sleeve rotates as it is forced to the bottom by the plunger. The opening 16 where the shaft 11 passes through is the only place for the fluid to enter. In case the air pressure has not lifted the ball 8 there would be a very small amount of sand 10 which could reach that part. The opening 9 is merely to let the air out in case there is a surplus of fluid in the hole. This allows the plunger to drop freely. To operate the pump when it is lowered to the bottom of the hole and the cutter 31 is setting on the bottom thereof, it will be noted that 35 is open and the upward stroke of the plunger will start 31 rotating and the sucker lifting material up from the cylinder of the pump, ejecting the fluid out of the opening 36 and any sand which may have gotten up through the opening 27 and lodged on top of the sucker valve. If desired the plunger may be let down as many times as the operator sees fit. Ordinarily it will load to its full capacity the first time it is lifted, as the valve 32 closes when the sucker valve passes below the opening 36, thereby leaving a supply of fluid or material between the valve 32 and the opening 36. If the plunger is let down a second time and the cylinder is half full of sand it will only go down that far. Any tendency for the sand to get on top of the sucker valve and cause the plunger to 35 become stuck in the pump is prevented by the cup valve with its thin edge.

When operating the pump in a caving formation, the plunger may be lifted as many times as the operator sees fit to operate the member 31 to crush such formation. The rotating member 31 will crush any formations of this sort which may be picked up through the openings in the spider 35.

It will be understood that I desire to comprehend within my invention such modifications as may be necessary to adapt it to varying conditions and uses.

Having thus fully described my invention, what I claim as new and desire to secure by Letters Patent, is:—

1. In combination, a cylinder, a pump rod, a piston working therein, a material cutter and means to rotate said material cutter telescoping within said pump rod.

2. In combination, a cylinder, a pump rod, a piston working therein, a material cutter and means to rotate said material cutter telescoping within said pump rod, and means associated with said cutter for cooperating and elevating said material.

3. In combination, a cylinder having an open lower end and exit openings at the upper end, a pump rod operating therein, a piston adapted to reciprocate on said pump rod loosely engaging within the walls of said

cylinder, a material crushing member carried at the bottom of said cylinder and means for rotating said crusher as said pump rod reciprocates.

4. In combination, a cylinder having an open lower end and exit openings at the upper end, a pump rod operating therein, a piston adapted to reciprocate on said pump rod loosely engaging within the walls of said cylinder, a material crushing member carried at the bottom of said cylinder and means for rotating said crusher as said pump rod reciprocates, and means carried within the end of said pump rod for engaging with the rotating means of the crusher to rotate it. 70

5. In combination, a cylinder having an open lower end and exit openings at the upper end, a pump rod operating therein, a piston adapted to reciprocate on said pump rod loosely engaging within the walls of said cylinder, a material crushing member carried at the bottom of said cylinder and means for rotating said crusher as said pump rod reciprocates, and means carried within the end of said pump rod for engaging with the rotating means of the crusher to rotate it, said pump rod being adapted to receive said rotating means telescopically within the 85 rod.

6. In combination, a cylinder having an open lower end and exit openings at the upper end, a pump rod operating therein, a piston adapted to reciprocate on said pump rod loosely engaging within the walls of said cylinder, a material crushing member carried at the bottom of said cylinder and means for rotating said crusher as said pump rod reciprocates, and means carried within the end of said pump rod for engaging with the rotating means of the crusher to rotate it, said pump rod being adapted to receive said rotating means telescopically within the 100 rod, said chamber in which the rotating means rotates within the rod having a vent opening at the upper end and a check valve 105 therefor, whereby the opening is opened upon the descent of the pump rod and its piston.

7. In combination, a cylinder having an open lower end and exit openings at the upper end, a pump rod operating therein, a piston adapted to reciprocate on said pump rod loosely engaging within the walls of said cylinder, a material crushing member carried at the bottom of said cylinder and means for rotating said crusher as said pump rod reciprocates, and means carried within the end of said pump rod for engaging with the rotating means of the crusher to rotate it, said pump rod being adapted to receive said rotating means telescopically within the 115 rod, said chamber in which the rotating means rotates within the rod having a vent opening at the upper end and a check valve 120 therefor, whereby the opening is opened upon the descent of the pump rod and its piston.

8. In combination, a cylinder having an open lower end and exit openings at the upper end, a pump rod operating therein, a piston adapted to reciprocate on said pump rod loosely engaging within the walls of said 125 rod, said chamber in which the rotating means rotates within the rod having a vent opening at the upper end and a check valve 130 therefor, whereby the opening is opened

upon the descent of the pump rod and its piston, and elevating means associated with said material crusher means for cooperating and elevating the material.

- 5 8. In combination, a cylinder having an open lower end and an exit opening at the upper end, a pump rod having a head and a collar spaced therefrom, a reciprocating loosely-fitting piston working therebetween, 10 a sleeve therein communicating with the interior of said piston rod which is hollow, a rotating shaft and worm thereon within said sleeve and the chamber within the piston rod, means on said sleeve for engaging 15 with the end of the piston rod to prevent its rotating, and means on the sleeve for engaging with the worm to cause it to rotate, and a cutter on the bottom of said rotating rod adapted to cut material.
- 20 9. In combination, a cylinder having an open lower end and an exit opening at the upper end, a pump rod having a head and a collar spaced therefrom, a reciprocating loosely-fitting piston working therebetween, 25 a sleeve therein communicating with the interior of said piston rod which is hollow, a rotating shaft and worm thereon within said sleeve and the chamber within the piston rod, means on said sleeve for engaging with
- the end of the piston rod to prevent its rotating, and means on the sleeve for engaging with the worm to cause it to rotate, and a cutter on the bottom of said rotating rod 30 adapted to cut material, said cutter consisting of an elevating worm having sharpened cutting faces at the end thereof.
- 35 10. In combination, a cylinder having an open lower end and an exit opening at the upper end, a pump rod having a head and collar spaced therefrom, a reciprocating 40 loosely-fitting piston working therebetween, a sleeve therein communicating with the interior of said piston rod which is hollow, a rotating shaft and worm thereon within said sleeve and the chamber within the piston rod, means on said sleeve for engaging 45 with the end of the piston rod to prevent its rotating, and means on the sleeve for engaging with the worm to cause it to rotate, and a cutter on the bottom of said rotating rod 50 adapted to cut material, said cutter consisting of an elevating worm having sharpened cutting faces at the end thereof, projecting beyond the end of the cylinder.

In testimony whereof, I affix my signature. 55

CHARLEY E. BURNS.
